UNITED STATES PATENT OFFICE.

JOHN J. RIGBY, OF BROOKLYN, NEW YORK.

DRAWING PRESS.

Application filed June 26, 1923. Serial No. 647,808.

To all whom it may concern:

Be it known that I, JOHN J. RIGBY, a citizen of the United States of America, residing in the borough of Brooklyn, city and State of New York, have invented certain new and useful Improvements in Drawing Presses, of which the following is a specification.

This invention relates to drawing presses of the type in which the blank to be drawn is gripped between a yielding blank-holder and a tool on a movable slide, and aims to provide improvements therein.

The invention provides a press of the type referred to in which the resistance to the movement of the blank-holder is uniform or constant throughout its movement, and in which the constant resistance may be regulated so as to be greater or less to suit the character of the drawing to be done. According to the invention, frictional means are provided for resisting the movement of the blank-holder, instead of elastic means heretofore generally employed.

The invention further provides a novel combination of elements constituting a press of the character described, including frictional means for resisting the movement of the blank-holder.

An embodiment of the invention is illustrated in the accompanying drawings, in which—

Figure 1 is a view in side elevation, partly in section, of a press embodying my invention.

Fig. 2 is a vertical section, running from side to side of the press, and on the line II—II, Fig. 3.

Fig. 3 is a view, mostly in plan, looking from the level indicated by the line III—III, Fig. 2.

Fig. 4 is a sectional view on the line IV—IV, Fig. 3.

Fig. 5 is a vertical sectional view illustrating a modification of the suspension means shown in Figs. 1 and 2.

Referring to said drawings, numeral 10 indicates a forming tool carried by a reciprocating slide 12, and adapted to coact with a complementary forming tool 15 seated upon the bolster plate 17 of the press. The tool 10 and its slide 12 may be reciprocated in any suitable manner, as by means of a crank-shaft 20 through a pitman connection 21.

Numeral 25 designates a yielding blank-

holder, adapted to coact with the reciprocating forming tool to grip the margin of a blank X (Fig. 2) during the drawing of said blank by the coaction of the drawing tools 10 and 15.

Friction means 30 are provided for resisting the movement of the blank-holder by the said tool 10. These means are adapted to oppose a substantially uniform or constant resistance to the movement of said blank-holder by the said tool 10.

The friction means 30 preferably consists of one or more slides 32, and means for clamping or frictionally pressing upon said slide or slides.

The means for clamping the slide or slides 32 conveniently consists of a support 34 for said slides, and a clamping plate 36, adapted to be drawn towards said support 34 by means of screws 38 or like, thereby clamping said slides 32 between the support 34 and the clamping plate 36, and thereby preventing movement of said slides 32, except under the action of a considerable force sufficient to overcome the frictional contact or binding force of said parts 34 and 36 on said slides 32.

It has been found in practice to give greater uniformity of resistance to have the clamping plate 36, or said plate 36 and the support 34, bear upon said slides 32 through rollers 40 or rollers 40, 41. In such case a greater or less part of the friction is transmitted to the bearings of the rollers, which in the present instance are pins or shafts 44 passing through said rollers and supported in suitable holes drilled in said support 34 and plate 36.

In order to attain a fine adjustment of the clamping force of the plate 36 on the slides 32, it has been found desirable to provide stops 48 between the said plate 36 and the support 34. These stops 48 are preferably screw-threaded, and the fine adjustment of the clamping plate is effected by turning the threaded stops 48 in such manner as to take off from the slides 32 some of the pressure exerted thereon by the screws 38, and transmitted thereto by the said clamping plate 36.

It will be understood that the clamping force acting on the slides 32, and hence the amount of resistance to the movement of said slides 32, may be adjusted so as to be greater or less, by turning the screws 38. After this primary adjustment has been ob-

tained, the fine adjustment may be effected by turning the screw stops 48 in the manner just described.

The motion of the blank-holder 25 is conveniently transmitted to the slides 32 through pins 50 passing through said bolster 17, and bearing upon a plate 52 on the underside of said bolster. For compactness and simplicity of construction, the 10 slides are conveniently arranged to move at right angles to the direction of movement of said blank-holder 25 and plate 52. To this end, a wedge piece 55, in the form of the frustum of a cone, is conveniently interposed between said plate 52 and the ends of said slides 32, the said slides 32 being conveniently arranged radially around the axis of said cone. The ends 57 of said slides 32 are preferably tapered to correspond to 20 the taper of the sides of said frusto-conical wedge piece 55. A pin 59 may be provided for guiding said wedge piece.

The employment of wedge piece 55 is of advantage in reducing the amount of clamping force exerted by the clamping plate 36, and hence the amount of resistance developed by the slides 32, to oppose the movement of said blank-holder 25. The pressure transmitted by the blank-holder to the cone 30 55 will have two components, one directed downwardly, and the other in line with the movement of said slides 32. Consequently, to produce a given resistance to the movement of the blank-holder 25, it will only be necessary to provide sufficient resistance to the movement of the slides 32 to overcome so much of that component of the force transmitted to the wedge piece 55 which acts in line with the direction of movement of 40 said slides 32 as is equal to the given resistance. This provides a convenient means of reducing the size of the slides 32 and their clamping means.

Suitable means 60 are provided for resetting, or, restoring to initial position, the slides 32 after each movement of the blank-holder 25. This resetting means 60 is conveniently in the form of a part 62, here shown as a ring attached to a reciprocating 50 part of the press, as the slide 12, and having an inclined face or faces 64 thereon adapted to contact with the slides 32, and move these slides in a direction opposite to that in which they are moved by the said 55 wedge piece 55. The parts or ends 66 of the slides which come in contact with the inclined faces 64 are conveniently tapered to correspond to the taper of said cam faces. Rods 68 passing through the bolster plate 60 conveniently serve as a means for connecting the resetting part or ring 62 to the reciprocating slide 12.

The supporting plate 34 is conveniently hung from the underside of the bolster plate 65 17 by means of threaded rods 70 having nuts

72 thereon, Figs. 1-4, or from a central rod 80, Fig. 5, attached to the underside of the bolster plate, as indicated at 82, passing through the plate 52, wedge 55, and support 34, and having nuts 86 thereon for fastening 70 said support thereon.

There are preferably a plurality of clamping screws 38 (or of screws 38 and 48) spaced at different points of the clamping plate 36, as indicated in Fig. 3. By differentially adjusting the screws 38 (or screws 38 and 48) adjustments of the force with which the blank X is gripped between the blank-holder 25 and the tool 10, at different points, may be effected. This adjustment is 80 made to take care of variations in thickness of the stock from which the blank is cut, and of peculiarities of drawing due to shape of the dies, differences in the thickness of the blank, and physical characteristics of the 85 metal.

The invention may receive other embodiments than that herein specifically illustrated and described.

What I claim is:

1. A drawing press comprising a yielding blank-holder, a reciprocatory tool adapted to grip the margin of a blank between said blank-holder and tool for drawing the blank, and friction means for resisting the movement of said blank-holder, said friction means comprising members having frictional sliding engagement.

2. A drawing press comprising a yielding blank-holder, a reciprocatory tool adapted to grip the margin of a blank between said blank-holder and tool for drawing the blank, friction means for resisting the movement of said blank-holder, said friction means comprising members having frictional sliding engagement, and means for varying the amount of resistance of said friction means.

3. A drawing press comprising a yielding blank-holder, a reciprocatory tool adapted to grip the margin of a blank between said blank-holder and tool for drawing the blank, and friction means for resisting the movement of said blank-holder, said friction means comprising a slide and means for clamping said slide.

4. A drawing press comprising a yielding blank-holder, a reciprocatory tool adapted to grip the margin of a blank between said blank-holder and tool for drawing the blank, and friction means for resisting the movement of said blank-holder, said friction means comprising a slide and means for clamping said slide, said clamping means comprising a roller bearing upon said slide.

5. A drawing press comprising a yielding blank-holder, a reciprocatory tool adapted to grip the margin of a blank between said blank-holder and tool for drawing the blank, and friction means for resisting the

- movement of said blank-holder, said friction means comprising a slide and means for clamping said slide, said clamping means comprising a pair of rollers bearing upon said slide.
6. A drawing press comprising a yielding blank-holder, a reciprocatory tool adapted to grip the margin of a blank between said blank-holder and tool for drawing the blank, and friction means for resisting the movement of said blank-holder, said friction means comprising a slide and means for clamping said slide, and means for resetting said slide, said means comprising a part actuated by said reciprocatory part.
- 10 blank, and friction means for resisting the movement of said blank-holder, said friction means comprising a slide and means for clamping said slide, and a wedge piece bearing against the end of said slide adapted to be driven by said blank-holder.
- 15 7. A drawing press comprising a yielding blank-holder, a reciprocatory tool adapted to grip the margin of a blank between said blank-holder and tool for drawing the blank, friction means for resisting the movement of said blank-holder, said friction means comprising a slide and means for clamping said slide, and means for resetting said slide, said means comprising a reciprocatory part having an incline for engaging the said slide and pushing it in the reverse direction to the push of said wedge.
- 20 8. A drawing press comprising a yielding blank-holder, a reciprocatory tool adapted to grip the margin of a blank between said blank-holder and tool for drawing the blank, friction means for resisting the movement of said blank-holder, said friction means comprising a roller bearing upon said slide, and a wedge piece bearing against the end of said slide adapted to be driven by said blank-holder.
- 25 9. A drawing press comprising a yielding blank-holder, a reciprocatory tool adapted to grip the margin of a blank between said blank-holder and tool for drawing the blank, friction means for resisting the movement of said blank-holder, said friction means comprising a slide and means for clamping said slide, and means for resetting said slide.
- 30 10. A drawing press comprising a yielding blank-holder, a reciprocatory tool adapted to grip the margin of a blank between said blank-holder and tool for drawing the blank, friction means for resisting the movement of said blank-holder, said friction means comprising a slide and means for clamping said slide, and means for resetting said slide, said means comprising a reciprocatory part having an incline for engaging the said slide and pushing it in the reverse direction to the push of said wedge.
- 35 11. A drawing press comprising a yielding blank-holder, a reciprocatory tool adapted to grip the margin of a blank between said blank-holder and tool for drawing the blank, friction means for resisting the movement of said blank-holder, and means for varying the amount of resistance of said friction means, said latter means comprising a clamping device, and means for partly counteracting the clamping effect of said clamping device, to obtain a fine adjustment of the latter.

In witness whereof, I have hereunto signed my name.

JOHN J. RIGBY.
